CLAIM

The ornamental design for a camera lens holder, as shown and described.

DESCRIPTION

FIG. 1 is a front perspective view of a camera lens holder showing our new design.

FIG. 2 is a top, rear perspective view of the camera lens holder.

FIG. 3 is a front elevational view of the invention.

FIG. 4 is a bottom plan view of the invention; and, FIG. 5 is a sectional, left side elevational view taken along line 5-5 in FIG. 2.

The broken lines show environmental subject matter that form no part of the claimed design.
